TUBE BASE AND SOCKET

Julius Hirshmann, Hillside, N. J., assignor to Radio Corporation of America, a corporation of Delaware

Application August 3, 1933, Serial No. 683,434

3 Claims. (Cl. 250—275)

My invention relates to vacuum tubes and the like, and more particularly to bases and sockets for such tubes.

The conventional vacuum tube has a cup-shaped base with a flat bottom on which tubular contact pins are mounted in a circle near the rim to project perpendicularly from the bottom of the base, thus adding to the overall length of the tube. These tubular contact pins are connected to the electrode elements of the tube by leading-in wires threaded into and soldered to the pins. The conventional socket has spring contacts which engage the contact pins of the base. The socket contacts extend radially outward and are fastened at their ends or intermediate their ends to the bottom of the socket by rivets or the like. The socket is inherently large and bulky, and extends considerably beyond the outline of the base of the tube.

An increase in the number of contact pins on the base decreases the spacing between the pins, increases the tendency for voltage breakdown through the base, and greatly increases the difficulty of basing the tube particularly the threading of the leading-in wires into the contact pins. The number of contacts which can be accommodated by the conventional socket has likewise reached a practical limit because of lack of space and because of the increase in the tendency of voltage breakdown through the socket. Assembly of the socket due to the number of parts required is likewise made more difficult.

Not only has the practical limit been reached in the number of contacts which can be mounted in a conventional way in tube bases and sockets of conventional size, but tube bases and sockets only about one-half the conventional size must be made with as many or even more contacts than the bases and sockets of conventional size. The usual number of conventional contact pins cannot be mounted in the conventional way on the smaller base, yet a corresponding reduction in size of the contact pins will result in pins which are too weak for practical use, which do not have enough contact area and which offer very great difficulty in the threading of the leading-in wires into the pins. Furthermore, there is a practical limit in the reduction of the diameter of the contact pins and of the leading-in wires, as the wires must be sufficiently large to carry the necessary current and also stiff enough to thread easily into the pins, which must, of course, have a bore somewhat larger than the wire.

A reduction in the size of the conventional socket and its contacts will result in contacts which

are too weak for practical use, which do not have sufficient contact area, and which increase the difficulty of assembling the socket. It would not be practical to materially reduce the size of contacts in the socket and still have these contacts properly cooperate with pins on the tube base which were not materially reduced from conventional size.

The conventional contact pin is in effect riveted into the base by upsetting or spinning the inner end of the pin over the inside of the bottom of the base. The inner end is thus enlarged and in effect increases the diameter of the pin so that more room is required for spacing between the pins. As it is not feasible to reduce the diameter of the pins, the space required for fastening the pins to the base cannot be reduced, nor can smaller contacts be used, as the conventional socket contact is larger than the base pin which it engages.

One object of my invention is to provide a base and socket which can be made smaller than the conventional base and socket and yet have as many or even more contacts of ample area and properly spaced so that the electrical and mechanical properties of the smaller base and socket are ample to meet all requirements.

Another object of my invention is to provide a base so constructed that the attachment of the leading-in wires to the contacts is simple and easier than soldering to tubular contact pins.

A further object of my invention is to provide a base and socket having mechanically strong contacts which are so arranged that more angular space is made available for the contacts than in the conventional base and socket and which are made to occupy less angular space on the base and socket than the contact pins and socket contacts commonly used, yet have as great or even greater contact area than the conventional pin and socket contacts.

Still another object of my invention is to provide improved base and socket contacts which are simple and inexpensive to make.

These and other objects will appear herein-after.

The novel features which I believe to be characteristic of my invention are set forth with particularity in the appended claims, but the invention itself will be best understood by reference to the following specification taken in connection with the accompanying drawings in which

Figure 1 shows a vacuum tube having a base constructed in accordance with my invention.

Figure 2 is an enlarged top view of the base shown in Figure 1 with the bulb removed.

Figure 3 is a longitudinal section of the lower end of the tube shown in Figure 1 taken along the line 3—3 of Figure 2.

Figure 4 is an enlarged bottom view of the base shown in Figure 1.

Figure 5 is a perspective view of a contact terminal made in accordance with my invention.

Figure 6 is a perspective view of a socket constructed in accordance with my invention and the tube shown in Figure 1 which cooperates therewith.

Figure 7 is a top view of the socket shown in Figure 6 with parts broken away to show details of construction.

Figure 8 is a longitudinal section of the socket shown in Figure 6 taken along the line 8—8 of Figure 7.

Figure 9 is a horizontal section of the socket shown in Figure 6 taken along the line 9—9 of Figure 8.

Figure 10 is a perspective view of a socket contact made in accordance with my invention.

The vacuum tube shown in Figure 1 of the drawings has an evacuated bulb 10 enclosing the usual cathode, anode, and grid or grids. The bulb 10 has secured to it by cement a tubular base preferably molded from insulating material and comprising a collar 11 provided with the usual indexing pin 12, and a lower portion 13 of smaller outside diameter and smaller inside diameter than the collar for providing an inside shoulder 14. In the particular device shown in Figures 1, 2, 3, and 4, the base is provided with apertures 15 which extend through the base from the interior of the base at the top of the shoulder 14 to the exterior of the base at the lower end of the collar 11. The portion 13 of reduced diameter has at its lower end slots 16 directly in line with the apertures 15. Flat ribbon contacts 17 extend through the apertures 15 and slots 16 and are wrapped longitudinally around the portion 13 of reduced diameter as shown to provide flat contact faces on the outside of the base. The ends of the ribbon contacts are brought together and welded to fasten the contacts in place on the base and also to form connecting lugs 18 and 19 which facilitate and simplify the connecting of the lead wires 20 to the base contacts 17.

When the tube is based the connecting lugs 18 and 19 practically adjoin the outer ends of the lead wires 20, which extend through the tubular portion 13 of the base shell. The ends of the lead wires are inserted between and then welded to the connecting lugs 18 and 19, whereby threading of the lead wires into tubular contact pins is eliminated, and a good electrical connection made more easily than by soldering. The contacts are backed and supported by the base shell 13 and although narrow are held sufficiently rigid to constitute a strong rigid contact.

As the width of the ribbon contact may be less than the diameter of the conventional tubular contact, and since the ribbon contacts are spaced around the exterior of the base instead of in a circle on the bottom of the base near the rim, as is done with tubular contacts, more of such contacts may be accommodated on a base of the usual size, or the size of the base can be materially reduced and still the maximum number of contacts now feasible for the usual size base can be used. The flat contacts have ample

contact area, at least as much as the conventional contact, and because of their being mounted on the side of the base the tube is shortened and less head room required for it.

The flat contacts 17 may to advantage be made of nickel which is easily worked and welded. They may be made in various ways, but I prefer to cut them from metal ribbon and form them automatically by machine, as it is easier to shape the metal ribbon into a flat contact than it is to make the usual type of tubular contact.

It is obvious that the base can be registered with the socket in various ways; for example, by placing the contacts nonsymmetrically around the shell or providing studs or projections on the base shell to enter corresponding slots in the socket. I prefer to register the base and socket by means of a stud or pin 12 for this purpose.

A socket for the vacuum tube with the base shown in Figures 1 to 4 inclusive is shown in Figures 6 to 9 inclusive. It comprises separate upper and lower parts which telescope and between which the socket contacts are clamped. The tubular upper part 29 of the socket has a central opening 30 large enough to receive the tube base 11 and has in one side an indexing slot 31 for the stud or pin 12 on the base of the tube. This upper part 29 has a flange 32 with bosses 33 for attaching the socket to a panel, and a shoulder 34 on the interior wall for limiting the extent to which the base may be inserted in the socket.

When the base is home in the socket the base contacts 17 are in registry with slots 35 in the lower end of the part 29 of the socket as most clearly shown in Figures 8 and 9. Spring contacts 37 project through these slots and have flat portions 38 which are resiliently forced into engagement with the base contacts by spring portions 39. Connections to the contacts are made by connecting lugs 40 on the socket contacts.

The contacts 37 are held in place by being clamped between the upper part 29 grooved to receive the contacts and the lower cup-shaped part 41 of the socket, which has a lip 42 to cooperate with the flange 32 of the upper part. The two parts of the socket are riveted together by rivets 43. The bottom of the lower cup-shaped part 41 has on the inside an annular channel 44 in which the lower ends of the contact springs rest, and by which the extent of inward movement of the spring contact is limited. Apertures 45 in the bottom of the socket permit particles of dirt and the like to fall out of the socket through the bottom. An annular collar 46 at the center of the bottom part 41 prevents foreign objects dropping into the socket far enough to short circuit the contacts 37.

It will be obvious that when the base is inserted in the socket, the base contacts 17 will engage the flat part 38 of the socket contacts 37 and make a good contact of ample area. The wiping action between the contacts as the base is inserted in the socket insures clean contact surfaces, and the spring 39 of the socket contact insures sufficient pressure between the contacts. The socket contacts 37 for a socket constructed in accordance with my invention can be made in much the same way as the base contacts 17.

It will be seen that I have provided a base and socket in which the maximum number of contacts which it is now feasible to use for the conventional base and socket can be materially increased and still have the base and socket fully

meet the electrical and mechanical requirements for such devices. In accordance with my invention I can reduce the size of the usual base and socket and still properly accommodate as many 5 contacts as can now be used on a base and socket of the usual size. The threading of lead wires into tubular contact pins has been eliminated thus expediting manufacture. The electrical connections between the contacts and the lead 10 wires have been materially improved and by means of my invention I provide simple contacts which can be manufactured cheaply and easily from metal ribbon for both the base and socket. The embodiment of the invention illustrated 15 and described herein has been selected for the purpose of setting forth the principles involved, but it will be apparent that various modifications may be made to meet the different conditions encountered in use and I, therefore, intend to 20 cover all modifications within the scope of the appended claims.

What is claimed as new is,—

1. A vacuum tube base including a tubular member having at one end a collar of larger 25 diameter than the rest of the member and spaced slots in the other end, said tubular member having apertures spaced around its periphery intermediate its ends and in line with said slots, and ribbon contacts extended through said apertures 30 and said slots and longitudinally wrapped around said base between said apertures and said slots to provide flat contact surfaces and to space said contacts around said tubular member, each of

said contacts having its ends fastened together to secure the contact to said tubular member and to provide lugs between which a lead wire is attached to the contact.

2. A vacuum tube base including a tubular 5 member having apertures spaced around its periphery intermediate its ends and spaced slots in one end in line with said apertures and U-shaped ribbon contacts extended through said apertures and said slots and longitudinally wrapped around 10 said tubular member between said apertures and said slots to provide external flat contact surfaces and to space said contacts around said tubular member, each of said contacts having its ends fastened together adjacent the slots to secure the contact to said tubular member and to provide lugs at the inner surface of the tubular member to which a lead wire is attached.

3. A vacuum tube base including a tubular member having a shoulder on the interior thereof 20 of, said member having spaced apertures extending through said member at said shoulder and having slots in one end thereof in line with said apertures, and U-shaped ribbon contacts extended through said apertures over said shoulder 25 and wrapped around said member to lie flat against said member with the ends of said contacts extended through and fastened together adjacent said slots to secure said contacts in position around said member and to provide lugs at the 30 inner surface of said tubular member.

JULIUS HIRMANN.
